[57] CLAIM

The ornamental design for an illuminated sign, as shown
and described.

DESCRIPTION

FIG. 1 is a top plan view of an illuminated sign showing
the new design, the bottom plan view being a mirror
image thereof;

FIG. 2 is a front elevational view thereof;

FIG. 3 a left side elevational view with the right side
being a mirror image thereof; and

FIG. 4 is a rear elevational view thereof;

FIG. 5 is a perspective view as seen from the front and
one side and end.

Fig. 1.

Fig. 3.

Fig. 2.
